APPARATUS FOR FORMING SHOE SHANKS

William Joseph Reicheneder and George W. Miller, St. Louis, and Walter M. Wolf, St. Louis County, Mo., assignors to Convex Heel Covering Co., St. Louis, Mo., a corporation of Missouri

Application September 13, 1950, Serial No. 184,616

7 Claims. (Cl. 12—60)

1

This invention relates in general to shoe manufacture and, more particularly, to certain new and useful improvements in apparatus for forming shoe shanks.

Heretofore, the customary practice in the shoe industry for forming shanks of fibrous material and the like has been to die-out shank blanks from superimposed sheets of fiber board and related material by means of a clicking machine. This operation entails periodic stacking of the sheets before operation of the machine and manipulation of the die prior to each stroke of the ram to assure reasonably economic utilization of the stock. Upon completion of this punching operation the blanks must then be transported to a skiving machine to which each is individually fed for receiving a bevel on its forward margin. It will thus be seen that multiple handling of the stocks and blanks is required in the performance of this method with a consequent relatively high cost per unit because of the inherent limitation upon the number of shanks which may be produced in any one working period.

It is an object of the present invention to provide an apparatus for forming shoe shanks which incorporates means for serving board stock into strips of desired widths, means for advancing the strip stock to a skiving unit for beveling one margin thereof, and means for progressing the beveled strip stock to a punch press in timed relation to the operation of the press for punching out the maximum number of shanks from the strip.

It is a still further object of the present invention to provide apparatus of the type stated which is durable and reliable in usage; contains adjusting means to permit production of shanks of various lengths and thicknesses; and the operation of which requires the services of a limited number of relatively unskilled personnel.

With the above and other objects in view, our invention resides in the novel features of form, construction, arrangement, and combination of parts presently described and pointed out in the claims.

In the accompanying drawings (three sheets)—

Figure 1 is a front view of a machine for forming shank blanks constructed in accordance with and embodying the present invention;

2

Figure 2 is a transverse sectional view taken along line 2—2 of Figure 1;

Figure 3 is a rear view of the machine;

Figure 4 is a transverse sectional view taken along line 4—4 of Figure 1;

Figure 5 is a transverse sectional view taken along line 5—5 of Figure 4;

Figure 6 is a transverse sectional view taken along line 6—6 of Figure 2;

10 Figure 7 is a transverse sectional view taken along line 7—7 of Figure 6;

Figure 8 is a transverse sectional view taken along line 8—8 of Figure 1;

15 Figure 9 is a transverse sectional view taken along line 9—9 of Figure 8;

Figure 10 is a transverse sectional view taken along line 10—10 of Figure 1;

Figure 11 is a transverse sectional view taken along line 11—11 of Figure 10; and

20 Figure 12 is a perspective view of a formed shank.

The method of this invention for forming shoe shanks comprises cutting single sheets of fiber board or related leather-simulative material into strips having widths which are substantially equivalent to the length of the shanks to be formed. The strips are then skived along one longitudinal margin thereof at any desired angle. The beveled strips may then be fed to a suitable

25 type press for dieing-out shanks therefrom. The shanks thus punched are complete and ready for use since the requisite bevel has been cut during the skiving operation. As will be seen, the practice of this method does not require

30 handling of the formed shanks other than to pack same for ultimate transportation to a shoe assembly point. There is total elimination of the laborious and time-consuming step of feeding individual shank blanks to a skiving machine since

35 the skiving operation herein has been accomplished in a facile manner upon the strip stock. Furthermore, the strip cutting operation prevents untoward waste of material.

Although the method taught herein may be 40 performed by various types of apparatus, as well as, if necessary, by a hand-wielded knife, the drawings illustrate a preferred type of apparatus for shoe shank production according to the present method. Referring to the various figures 45 in detail by reference characters, A designates

a shoe shank forming machine comprising a feeding table B having legs 1 and a rectangular top 2 dimensioned for conveniently supporting a sheet of fiber board C and the like. Upstanding from the rearward margin of the top 2 is a flange 3 having an integrally formed forwardly projecting, relatively short plate-like member 4 in elevated, parallel relation to the table top 2 to serve as a depressant upon any undulations or other irregularities in the surface of the board C caused by warping or similar causes.

Adjacent the feeding table B and abutting thereagainst at one of its ends is a relatively elongated central frame section D having leg members 5 and vertically spaced, parallel lower and upper plates 6, 7, respectively, secured at their corners, as by welding, to the legs 5, the said upper plate 7 being in lowered relation to the top 2 of the feeding table B.

Bolted to the upper face of the plate 7 at the end thereof adjacent the feeding table B is a generally rectangular frame 8 of a cutter unit E, the frame 8 having an opening 9 in its forwardly presented lateral wall (see Figure 4). Extending transversely across the frame 8, between and journaled in the lateral walls thereof, above and below the opening 9 is a pair of parallel shafts 10, 11, respectively, having their rearward ends projecting through the rearward lateral wall of the frame 8. Mounted on the projecting end of the shaft 10 is a pinion 12 in meshing engagement with a gear 13, keyed or otherwise engaged upon the projecting end of the shaft 11. Outwardly spaced from the gear 13 on the shaft 11 is a sprocket wheel 14 drivingly connected by a chain 15 trained thereabout to driving means which will be described in detail hereinafter.

Adjustably mounted, as by a set screw, substantially centrally upon the shaft 10 is a rotary cutter 16 having its lower facial portion engaged against the upper portion of a similar rotary cutter 17 movably secured upon the shaft 11. Spaced from the cutter 16 on either side thereof and suitably mounted on the shaft 10 are hold-down rollers 18, 19, for path-defining relationship with similar type rollers 20, 21, mounted on the lower shaft 11, respectively laterally outwardly of the rollers 18, 19, the path formed thereby being aligned with the opening 9 and the upper surface of the top 2 of the feeding table B for receiving board stock C as same is fed to the cutter unit E for severing operation. As the distance between the cutters 16, 17, and the rearward lateral wall of the frame 8 determines the width of the strip to be cut, the lateral adjustability of the cutters 16, 17, readily adapts the cutter unit E for providing strips of selected widths to permit the machine A to produce shanks of an extensive range of lengths. During strip cutting operation the excess portion of the board C will proceed through the opening 9 for easy manual removal. In the economical performance of the operation of the machine A, it is preferable that the width of the strip so cut approximate as closely as possible the length of the shank to be formed therefrom so that waste will be at a minimum. As will be seen in Figures 4 and 5, a pair of wire-like members 21' are associated with the cutter unit E for guarding against inadvertent movement of the stock C below the path through the cutter unit E.

Disposed in elevated and parallel relation to the upper plate 7 of the frame section D is an

elongated conveyor plate 22, the upper surface of which is aligned with the path through the cutter E and the upper surface of the top 2 of the feeding table B for receiving strip sections C'. Said conveyor plate 22 extends from immediately adjacent the cutter E to a point in alignment with the opposite end margin of the plate 7, and is supported along its under face upon L-shaped support members 22'. Rigidly secured to said members 22', at opposite sides of the conveyor plate 22 adjacent the frame 8 of the cutter E, are the upper ends of a pair of aligned uprights 23 suitably secured, as by bolts, at their lower ends to the plate 7. At its opposite end the conveyor plate 22 is upheld by a pair of channel-shaped, inwardly opening post members 24, 24', bolted to the support members 22' and the plate 7, and which project upwardly beyond the conveyor plate 22. Across the upper end of each of the post members 24, 24', is a closure plate 25. Providing additional support for the conveyor plate 22 is a second pair of post members 26, 26', each having a closure plate 25 and being spaced from the post members 24, 24', a distance approximately equivalent to one-third the length of the conveyor plate 22.

Welded within the channel of each post 26, 26', is a bearing block 27, 27', respectively, within which is journaled a shaft 28 extending transversely therebetween and projecting outwardly through a suitable aperture in the rearward post 26' at its rearward end for engagement thereon of a pair of spaced sprocket wheels 29, 30, forming a part of the drive means hereinafter fully set forth. Disposed upon the shaft 28 is a feed roller 31 extending between the inner margins of the posts 26, 26', and having its upper portion protruding through a transverse slot 32 in the plate 22, the upper surface of which is substantially tangential to the roller 31. Freely slidable through gravity within the channels of each of the posts 26, 26', upwardly of the bearing blocks 27, 27', are second bearing blocks 33, 33', respectively, which support the ends of a shaft 34 extending transversely therebetween in parallel relation to the shaft 28. Secured upon the said shaft 34 is a hold-down roll 35. Drilled in the upper face of each of the bearing blocks 33, 33', is an upwardly opening recess 36 for receiving the lower end of a compression spring 37, the upper end of which bears against a flanged cap 38, maintained in position by an adjustment screw 39, which projects downwardly through a suitable aperture in each closure plate 25, and is provided with an enlarged knurled head 40. Engaging the shank of each screw 39 beneath the head 40 is a lock nut 41 to permit securement of the screw 39 in desired position to cause the springs 37 to resist undue upward movement of the bearing blocks 33, 33', after same have been raised by passage of the strip stock C' beneath the hold-down roll 35 and thereby assure adequate downwardly directed guiding pressure on said strip C' as it progresses along the conveyor plate 22.

The end posts 24, 24', similarly support upper and lower shafts 42, 42', respectively, for engagement thereon of opposed feed rollers 43, 43', respectively, which are identical with the feed roll 31. Said end posts 24, 24', are each provided with knurled head adjustment screws 44 in association with compression springs (not shown) for spring loading the upper shaft 42 in like manner as the posts 26, 26'. The lower shaft 42' projects out-

wardly beyond the rear face of the post 24' and has mounted thereon a pair of spaced sprocket wheels 45, 46.

Mounted on the upper plate 7 of the frame section D intermediate the posts 26, 26', and the uprights 23, 23', is the base 47 of a skiving machine F having to the rear thereof an integrally formed arm 48 projecting upwardly beyond the plate 22 and being bored to provide a pair of vertically spaced bearings 49, 50. Journalled in the upper bearing 49 and projecting at its ends therethrough is a relatively short shaft 51 having keyed upon its forwardly projecting end a peripherally serrated feed roll 52 and disposed on its rearwardly projecting end is a pinion 53 meshingly engaged with a gear 54 secured upon a relatively long shaft 55 supported for rotation in, and projecting through, the bearing 50. Mounted upon the forward projecting end of said shaft 55 is a serrated feed roll 56 for co-operation with the feed roll 52 for gripping the strip of material C' by its rearwardly presented longitudinal margin to pull same therebetween for cutting a bevel upon its under face by a blade 57 adjustably mounted upon the skiving machine F for setting at the desired angle to the horizontal. With reference to Figures 2 and 7, it will be seen that the conveyor plate 22 is provided with a suitable recess 58 in its rearward margin to permit the feed rolls 52, 56, and the blade 57 to be positioned within the path of the strip C' as it is moved along said conveyor plate 22. Coveringly disposed over the upper portion of the feed roll 52 is a partial housing member 52'.

The rearward end of the shaft 55 is journalled in a bearing 59 mounted on a frame section 60 which is secured at its lower end to the plate 7. Intermediate the bearing 59 and the gear 54 there is engaged upon the shaft 55 an enlarged sprocket wheel 61 and a smaller sprocket wheel 62. Trained about the sprocket wheel 61 is an endless drive chain 63 which extends downwardly and laterally and is engaged at its lower end about a sprocket wheel 63' keyed upon a shaft 64 supported by, and journalled in, a pair of spaced bearings 65, 66, bolted to the upper face of the plate 7. Also engaged upon the shaft 64 is a sprocket wheel 67 about which is engaged the lower end of the chain 15. The rearward end of the shaft 64 has engaged thereon a pulley 68 protruding through a suitable aperture 69 in the plate 7 and having disposed thereabout one end of a V-belt 70 engaging on its lower end a pulley 71 of reduced diameter mounted upon the end of a drive shaft 72 of a variable speed prime mover 73, conveniently positioned upon the plate 6 of the frame section D. The pairs of sprocket wheels 62, 39, and 29, 45, are drivingly connected by chains 74, 75, respectively (see Figure 2). Thus, upon actuation of the motor 73, rotation is imparted to the shaft 11 of the cutter E and the shaft 55 of the skiving machine F with consequent rotation of the respective co-operating shafts 10, 54, through the gears 13, 54, and the pinions 12, 53, respectively. By rotation of the shaft 55, drive is transmitted by the sprocket chain 74, 75, to the rollers 31, 43', respectively. It is to be pointed out that the sprocket wheels 62, 39, 29, 45, 46, are of the same size so that the shafts associated therewith will be rotated at a uniform rate.

Connected to the rearward margin of the conveyor plate 22 and extending therealong, substantially throughout its length, is an angle section 76 so disposed as to present its horizontal portion 77 in elevated relation to the conveyor

plate 22 and being removed therefrom a distance slightly in excess of the thickness of the stock normally utilized in the machine A. Parallel to, and spaced forwardly from, the angle section 76 in guideway-forming relationship therewith is an angle section 78 terminating at one end spacedly from the cutter E and being secured, as by welding, on the upper surface of its horizontal portion, at intervals to channel brackets 79. Transversely extending through the channels of the brackets 79 are guide bars 80 which are rigidly attached at one of their ends to the upper face of the horizontal portion 77 of the angle section 76 and are downwardly bent at their opposite ends for securement to the support strip 22'. Tapped in each bracket 79 is a threaded aperture 79' opening at its lower end into the channel thereof for receiving a knurled head set screw 81 which abuts against the guide bar 80 for adjustably maintaining the angle section 78 in desired spacial relationship to the section 76. Thus, by loosening the set screws 81, the angle section 78 may be moved forwardly or rearwardly by sliding of the brackets 79 along the guide rods 80 for forming a pathway with the section 78 of desired width for accommodating relatively snugly the particular strip of board stock C being used.

Positioned at the end of the central frame section D opposite to that adjacent the feeding table B is a punch press G having an electric motor 82 for rotation of a fly wheel 83 to effect reciprocal up and down movement of a ram 84 supporting on its lower end face a die 85 suitably formed for simultaneous punching of two shanks, in immediate side-by-side relationship, from the strip stock C' presented upon a bed plate 86. The bed plate 86 is aligned surface-wise with the conveyor plate 22 having one of its lateral margins immediately adjacent the roller 42'. On the opposite lateral end of the bed plate 86 there is disposed a pair of channel shaped posts 87, 87', in all respects similar to the posts 24, 24', being suitably provided with means (not shown) for journaling upper and lower shafts 88, 89, for supporting opposed feed rollers 90, 91, respectively, which are in parallel relation to the rollers 42, 42'. The shaft 89 projects outwardly beyond the rearward post 87' for supporting a sprocket wheel 92 about which is trained a chain 93 having its opposite end engaged about the sprocket wheel 46 whereby rotation will be imparted to the roller 91 upon actuation of the prime mover 73. Said sprocket wheel 92 is of the same size as the sprocket wheel 46 so that uniform speed is maintained throughout the work advancing means of the machine A.

Mounted on the bed plate 86 is an adjustable gage 94 for regulating the path through which the strip C' is moved across the said plate 86 so that conformity to the width of the passage created by the angle sections 76, 78, is obtained. The motor 82 of the punch press G is preferably connected to the same main switch (not shown) as the prime mover 73 so that upon operation of said switch the motors 73, 82, will be simultaneously actuated. Finally, there is provided an additional means for guiding the strips C' along the machine A, which comprises a strip of flat, relatively resilient metal stock 95 affixed at one end to the upper transverse portion of the frame 8 of the cutter unit E with its opposite end resting freely upon the conveyor plate 22 between the angle sections 76, 78, adja-

cent to the skiving machine F. It will thus be seen that the strip C' will move under the free end of the metallic strip 85, which will be engaged thereon for creating a downward pressure on the strip C'.

In operation, the rotary cutters 16, 17, are adjusted with relation to the rearward lateral wall of the frame 8 for the particular length of shanks to be formed and the angle sections 76, 78, are appropriately disposed to provide a path in conformance with the cutter adjustment. The gage 94 on the bed plate 86 of the press G is likewise correspondingly adjusted. After actuation of the prime mover 13 and the motor 32 of the punch press G a sheet of board stock C is placed upon the top 2 of the feeding table B with one margin thereof abutting against the flange 3 for assuring proper disposition of said sheet C which is then fed through the cutter E for severance of a strip C' of the predetermined width. The excess portion of the sheet is manually removed through the opening 9. As the strip C' progresses along the conveyor plate 22 during the strip forming operation, it will move within the guideway created by the angle sections 76, 78, and be gripped by the serrated feed rollers 52, 58, of the skiving machine F and fed to the blade 57 which will cut a bevel, designated generally 96, along the under face of the rearward longitudinal margin thereof. It will be seen that the feed rollers 52, 58, serve, in effect, a dual purpose, namely, that of feeding the strip C' to the blade 57, as well as advancing the said strip C' along the conveyor plate 22. Particular to note is the fact that the horizontally disposed portions of the angle sections 76, 78, provide a flattening effect upon any upward bulgings or other surface irregularities in the strips C' to expedite the advance of the strip C' without untoward obstructive engagement with various parts of the machine A and to assure that the most economical utilization will be made thereof. As the strip C' is thus moved through and past the skiving machine F, it will be advanced by the feed rollers 29, 42', the hold-down roller 35 serves primarily to ride along the upper surface of the now beveled strip C' to maintain same in contact with the feed roller 29. The roller 42 acts in conjunction with the roller 42' for feeding the beveled strip to the bed plate 86 of the press G. Each downward stroke of the said press G will cause two shanks S to be punched from the strip C' which shanks S will be in completed form and ready for utilization, since they have been previously provided with the requisite beveled margin. The punched strips C' will be pulled through the press G by the rollers 80, 91, for eventual collection of the formed shanks S.

It is to be especially observed that, since a punch press G operates at a predetermined number of strokes per minute, the strip C' must be advanced at a rate for presenting for each downward stroke of the press an uncut area of requisite dimension for two shanks with a minimum interval between the immediately previously punched portion. It is, therefore, most important that the speed of the prime mover 13 be so timed and regulated as to cause the strip conveying means, namely, the skiving feed rollers 52, 58, and the feed rollers 29, 42', 89, to advance the strip C' at such an appropriate rate relative to the speed of operation of the press G in order to permit the dieing out of the maximum number of shanks S from each strip C'.

It is, of course, apparent that the machine A may be utilized to accommodate shanks of any normal length, since the cutters 16, 17, may be adjusted commensurately with corresponding regulation of the guideway-forming means. It has been found through usage that the machine A will produce an estimated fifty thousand pairs of shanks during the accepted working period, which is about five times the number that can be produced by the use of a clicking machine with subsequent skiving of the individual shank blanks during a like period. Furthermore, despite this marked increase in productive capacity, the machine A merely requires the services of generally unskilled workers for feeding board stock C thereto and for collecting the formed shanks S. Therefore, by the operation of the machine A the cost per shank S is considerably lower than shanks produced by any method now currently practiced.

As stated hereinabove, the machine A thus described provides a most expedient means for performing the method of this invention but its utilization is not obligatory since other means may be used. Therefore, strips could be severed from superimposed stock and then individually fed to a skiving machine with the bevel strips being presented to a cutting machine having cooperative knives for cutting shanks therein. It is evident that the machine A provides preferable but not exclusive means for practicing the method described.

It should be understood that changes and modifications in the form, construction, arrangement, and combination of the several parts of the apparatus for forming shoe shanks and in the steps of its production may be made and substituted for those herein shown and described without departing from the nature and principle of the present invention.

Having thus described our invention, what we claim and desire to secure by Letters Patent is:

1. Apparatus for forming shoe shanks comprising adjustable cutting means for severing a strip of leather-simulative stock into strips of desired widths approximating the length of the shanks to be formed therefrom, a sheet-feeding table associated with said cutting means, a plate-like member secured to said table for depressing any upward bulgings in the sheet, an adjustable skiving unit for cutting a bevel of desired angularity along one longitudinal margin of the strips being cut by the cutting means, stamping means for stamping shanks from the beveled strips so that the forward portions of the shanks thus formed will coincide with the beveled portion of the strips thereby resulting in a finished shank, conveyor means for advancing the strips from the cutting means to the skiving unit and thence to the stamping means, and driving means for simultaneous actuation of the cutting means, skiving unit, stamping means, and conveyor means and adapted for presenting said strips to the stamping means in predetermined timed relationship to the operation thereof for stamping a maximum number of shanks from each strip.

2. Apparatus for forming shoe shanks comprising adjustable cutting means for severing a strip of leather-simulative stock into strips having widths approximating the length of shanks to be formed therefrom, a conveyor plate, adjustable means associated with said conveyor plate for forming a path therealong in conformity with the width of the strip cut by the cutting

means, strip advancing means provided in said conveyor plate, a skiving unit disposed in the path of the strip advanced along the conveyor plate for cutting a bevel in one longitudinal margin thereof, stamping means for stamping shanks from the beveled strips presented to said stamping means by the strip advancing means, and driving means for actuating said stamping means and said strip advancing means in predetermined timed relationship so that the maximum number of shanks may be stamped from the beveled strips.

3. Apparatus for forming shoe shanks comprising an adjustable cutter for severing a sheet of leather-simulative stock into strips having widths approximating the length of shanks to be formed therefrom, a feeding table associated with said cutter for facilitating the feeding of a sheet of stock thereto, a plate secured to said table and in elevated relationship to the upper surface thereof for depressing any upward bulgings or like surface irregularities in the sheet for facilitating the movement thereof through the cutter, an elongated conveyor plate for receiving on its upper surface the strip cut from the sheet stock by the cutter, means associated with said conveyor plate for exerting a downward pressure upon the upper surface of the strip to maintain same in relatively snug relationship upon the upper surface of the conveyor plate, adjustable members associated with said conveyor plate for defining a path therealong conforming in width to that of the strips cut by the cutter, strip advancing means provided in said conveyor plate for moving the strips along the paths thus defined, a skiving unit disposed in the path of the strip for cutting a bevel along one longitudinal margin thereof, a punch press for stamping shanks from the strips presented thereto by the strip advancing means so that the shanks thus formed will coincide on their forward margin with the beveled portion of the strips, and driving means for actuating the cutter, the skiving unit, the strip advancing means, and the punch press in predetermined timed relationship so that the beveled strip is fed to permit the maximum number of shanks to be stamped therefrom.

4. Apparatus for forming shoe shanks comprising an adjustable cutter for severing a sheet of leather-simulative stock into strips having widths approximating the length of shanks to be formed therefrom, a feeding table associated with said cutter for facilitating the feeding of a sheet of stock thereto, a plate secured to said table and in elevated relationship to the upper surface thereof for depressing any upward bulgings or like surface irregularities in the sheet for facilitating the movement thereof through the cutter, an elongated conveyor plate for receiving on its upper surface the strip cut from the sheet stock by the cutter, means associated with said conveyor plate for exerting a downward pressure upon the upper surface of the strip to maintain same in relatively snug relationship upon the upper surface of the conveyor plate, adjustable members associated with said conveyor plate for defining a path therealong conforming in width to that of the strips cut by the cutter, roller members associated with said conveyor plate for advancing the strips along the paths thus defined, a skiving unit disposed in the path of the strip for cutting a bevel along one longitudinal margin thereof, a punch press for stamping shanks from the strips presented thereto by the

said roller members so that the shanks thus formed will coincide on their forward margin with the beveled portion of the strips, driving means for actuating the cutter, the skiving unit, the strip advancing rollers, and the punch press in predetermined timed relationship so that the beveled strip is fed to permit the maximum number of shanks to be stamped therefrom, and means provided with said punch press and driven by the driving means for removing stamped strips from the press.

5. Apparatus for forming shoe shanks comprising adjustable cutting means for severing a strip of leather-simulative stock into strips of desired widths approximating the length of the shanks to be formed therefrom, a sheet-feeding table associated with said cutting means, sheet depressive means associated with said table for depressing any upward bulgings in the sheet, a skiving unit for cutting a bevel of desired angularity along one longitudinal margin of the strips being cut by the cutting means, stamping means for cutting shanks from the beveled strips so that the forward portions of the shanks thus formed will coincide with the beveled portion of the strips thereby resulting in a finished shank, conveyor means for advancing the strips from the cutting means to the skiving unit and thence to the stamping means, and driving means for simultaneous actuation of the cutting means, skiving unit, stamping means, and conveyor means and adapted for presenting said strips to the stamping means in predetermined timed relationship to the operation thereof for stamping a maximum number of shanks from each strip.

6. Apparatus for forming shoe shanks comprising cutting means for severing a strip of leather-simulative stock into strips having widths approximating the length of shanks to be formed therefrom, a conveyor plate, path defining means associated with said conveyor plate for the strip cut by the cutting means, strip advancing means provided in said conveyor plate, a skiving unit disposed in the path of the strip advanced along the conveyor plate for cutting a bevel in one longitudinal margin thereof, stamping means for cutting shanks from the beveled strips presented to said stamping means by the strip advancing means, and driving means for actuating said stamping means and said strip advancing means in predetermined timed relationship so that the maximum number of shanks may be cut from the beveled strips.

7. Apparatus for forming shoe shanks comprising an adjustable cutter for severing a sheet of leather-simulative stock into strips having widths approximating the length of shanks to be formed therefrom, a feeding table associated with said cutter for facilitating the feeding of a sheet of stock thereto, sheet depressive means associated with said table for depressing any upward bulgings or like surface irregularities in the sheet for facilitating the movement thereof through the cutter, a conveyor plate for receiving the strip cut from the sheet stock by the cutter, means associated with said conveyor plate for exerting a downward pressure upon the upper surface of the strip to maintain same firmly upon the conveyor plate, path defining means associated with said conveyor plate for the strip cut by the cutter, strip advancing means provided in said conveyor plate for moving the strips therealong, a skiving unit disposed in the path of the strip for cutting a bevel along one longitudinal margin thereof, stamping means for cutting shanks from the

the strips presented thereto by the strip advancing means so that the shanks thus formed will coincide on their forward margin with the beveled portion of the strips, and driving means for actuating the cutter, the skiving unit, the strip advancing means, and the stamping means in predetermined timed relationship so that the beveled strip is fed to permit the maximum number of shanks to be cut therefrom.

WILLIAM JOSEPH REICHENEDER.
